UNITED STATES PATENT OFFICE.

LEGRAND D. HARDING, OF COLFAX, WASHINGTON.

GRINDING-MILL.

SPECIFICATION forming part of Letters Patent No. 450,014, dated April 7, 1891.

Application filed October 4, 1889. Serial No. 326,010. (No model.)

To all whom it may concern:

Be it known that I, LEGRAND D. HARDING, of Colfax, in the county of Whitman and State of Washington, have invented a new 5 and Improved Grinding-Mill, of which the following is a full, clear, and exact description.

The object of the invention is to provide a new and improved grinding-mill which is simple and durable in construction, very effective 10 in operation, and especially designed for gradually reducing grain to different degrees of fineness and ultimately to flour and feed.

The invention consists of certain parts and details and combinations of the same, as will 15 be hereinafter fully described, and then pointed out in the claims.

Reference is to be had to the accompanying drawings, forming a part of this specification, in which similar letters of reference indicate 20 corresponding parts in all the figures.

Figure 1 is a side elevation of the improvement. Fig. 2 is an end elevation of the same. Fig. 3 is a sectional side elevation of the 25 grinding-rollers and feed-hopper. Fig. 4 is a sectional plan view of the grinding-rollers. Fig. 5 is a sectional plan view of a device for adjusting one of the grinding-rollers. Fig. 6 is a sectional side elevation of the same on the line $x-x$ of Fig. 5. Fig. 7 is an enlarged 30 end elevation of an eccentric-shaft. Fig. 8 is a side elevation of one of the hangers for the grinding-rollers. Fig. 9 is a side elevation, partly in section and with the casing removed, of two mills coupled together; and Fig. 10 is a side elevation of the feed-hopper 35 for the same.

The improved grinding-mill is provided with a hollow base A, carrying a casing B, in which are mounted to turn the grinding-rollers C and D, adapted to be held in frictional 40 contact with the stock passing between them at their peripheries, as is plainly shown in Figs. 3 and 4. The grinding-roller C is provided in its periphery near the middle with 45 an annular recess C', into which fits a correspondingly-shaped annular offset D', formed on the other grinding-roller D. Instead of forming the recess and offsets in the grinding-rollers, they may be produced by placing 50 together rollers of different diameters, as shown in Fig. 9. The grinding-rollers C and D are fastened on the shafts E and F, re-

spectively, mounted to turn in suitable bearings E' and F', respectively, located on the outside of the casing B and supported on the 55 pointed ends of screws E² and F², respectively, screwing in the forked ends of the hangers E³ and F³, respectively, passing through lugs A', formed on the base A, and supported at their lower ends on screws E⁴ and F⁴, respectively, 60 screwing in lugs A², also formed on the base A directly below the lugs A'. The screws E² and F² when properly adjusted are locked in place by suitable jam-nuts, as shown in Fig. 1. In a similar manner the screws E⁴ and F⁴ 65 are locked in place by jam-nuts E⁵ and F⁵, screwing against the underside of the lugs A².

On the hangers E³ and F³ are held adjustably the collars E⁶ and F⁶, respectively, adapted to abut against the under sides of the lugs 70 A'. By the means just described the hangers E³ and F³ can be conveniently raised and lowered, and the bearings E' and F' can be adjusted sidewise by the screws E² and F², respectively. 75

The shaft E is the driving-shaft, and is connected with suitable machinery for imparting a rotary motion to said shaft. On one end of the shaft E is secured a pulley K, over which passes a belt K', also passing over a pulley 8c K², secured in one outer end of a shaft L, extending transversely and mounted to turn in suitable bearings in the casing B. The part of the shaft L inside of the casing B is the feed-roll, (see Fig. 3,) above which is held the 85 hopper N, carrying a shaft N³, mounted to turn in the sides of the casing B. On one outer end of the shaft N³ is secured a weighted arm N⁴, which serves to press the lower edge of the hopper N toward the shaft L to regulate the amount of material passing from the hopper N over the feed-roll L to the grinding-rollers C and D. On the shaft N³ is also secured an arm N⁵, resting on a rod N⁶, on which is screwed a thumb-nut N⁷ against a coiled 95 spring N⁸. Said spring rests on a guideway N⁹, through which said rod passes loosely at its lower end, so that by screwing the thumb-nut up or down on the said rod N⁶ the arm N⁵ may be raised or lowered at its outer end, 100 and thereby the feed-hopper N may be moved toward or from the feed-roller L, thereby regulating the feed. The hangers F³ support the roller-shaft F, and are made horizontally ad-

justable, so as to throw the grinding-roller D out of frictional contact with the grinding-roller C whenever desired. The hanger F³ is for this purpose passed through an elongated 5 hole in the lug A', and its lower end is provided with a slot F⁷, (see Fig. 6,) into which passes the upper end of the set-screw F⁴, thus permitting a sidewise adjustment of the said hanger F³, and at the same time permitting 10 the screw F⁴ to support the said hanger.

The device P for adjusting the hangers F³ horizontally for the purpose of setting the rolls in grinding position is provided with a collar P', engaging the lower end of each 15 hanger F³, and in each collar P' screws a screw-rod P², provided on its outer end with a hand-wheel P³ for conveniently turning said screw. Each screw-rod P² screws in a collar P⁴, mounted on the eccentric end Q' of a shaft Q, 20 mounted to turn in suitable bearings in one end of the base A. (See Figs. 5 and 6.) Each eccentric end Q' of the shaft Q is provided with an aperture sufficiently large to permit the passage of the screw-rods P². A jam-nut 25 P⁵ screws on each of the screw-rods P² against the collar P⁴, so as to lock the screw-rod P² in place when the adjustment has been made.

On the shaft Q is held a downwardly-extending rod Q², which, when moved outward, 30 turns the shaft Q and moves the eccentric ends Q', so as to cause an inward movement of the collars P⁴, whereby the screw-rods P² move with the collars and push by the collars P' on the hangers F³, so that the grinding-roller D is moved out of contact with the grinding-roller C.

On the inside of the casing B, at each side and between the casing and the ends of the rolls, is fastened a padded ring to prevent the 40 dust from rising from the hollow base A.

The casing B is provided with a hinged cover B', which permits convenient access to the hopper N. The ends of the casing B are provided with doors B² for examining the 45 feeding device.

On the ends of the base A are arranged hinged doors A³ for examining the ground material as it leaves grinding-rollers C and D.

On the shaft E on the outside of the casing 50 B are held the pulleys G in frictional contact with the corresponding pulleys H, engaged at their peripheries by the inside of a ring I, preferably made of spring metal or other suitable material, said pulleys H having 55 flanged edges to guide said ring I. Each of the pulleys H is supported on a shaft H', mounted to turn in the forked end of a screw H², screwing in a nut H³, in which also screws a screw H⁵, fulcrumed at H⁶ on the base A. 60 By adjusting the nut H³ by means of its handles H⁴ the pulley H may be moved farther outward or inward, thus pressing with more or less force against the ring I and the pulley G and also against the pulley J, on the inside 65 of each ring I, directly opposite the pulley H and held loosely on the end of the shaft F, the said pulley J being also provided with

flanged edges to guide the said ring I. The ring I passes at its upper part between suitable guideways I', secured on the casing, and 70 is in frictional contact with the pulleys H and J. Thus when the shaft E is rotated the pulleys G on the said shaft impart a rotary motion to the pulleys H, and the latter, on account of their frictional contact with the rings I, and in conjunction with the pulleys J, rotate 75 said rings.

When the main drive-shaft E is set in motion, the pulley K is rotated, and by means of a belt K' imparts a rotary motion to the pulley K², by which the feed-shaft and the feed-roller L are rotated. Thus the stock to be ground falls between the grinding-rollers C and D and is carried downward and between 80 said rollers, partly by gravity and partly by 85 the rotary motion of the said rollers C and D. As the stock in contact with the periphery of the large parts of the roller C (or in contact with a large roller C, as the case may be) comes in contact with the small part of the 90 roller D (or with a small roller D, as the case may be) the small part or parts of the roller D 95 (or the small roller D, as the case may be) would be rotated by the large parts of the roller C or by a large roller C by frictional contact 100 with the moving chop or stock at a peripheral speed very nearly equal to that of the face of the driving-roller C; but as the large part of the roller D or a large roller D, as the case may be, comes in contact with the stock passing 105 between it and the small part of the roller C or with a small roller C, as the case may be, as is clearly shown in Fig. 11, the motion of the roller D is retarded by its frictional contact 110 with the stock passing between it and the small portion of the roller C (or a small roller C, as the case may be) in such a manner as to cause the said roller D to make the same number of revolutions in a given time 115 as is made by the said roller C. Thus by coupling together rollers with alternately large and small parts, or by coupling together alternate large and small rollers, as is clearly shown in Figs. 10 and 11, the peripheries of 120 the secondary line of rollers are differentially 125 and properly driven by imparting motion to the primary movers or dryers on the main drive-shaft E and using the stock passing between them and their opposing rolls instead of belting or gearing to drive them with a 130 proper differential at their peripheries.

The operation is as follows: When the main driving-shaft E is set in motion, the grinding-rollers D and C are rotated toward each other, as previously described, and at the same time 125 the feed-shaft L is turned, so that the material placed in the hopper N passes to the grinding-rollers C and D past the lower end of the swinging hopper N. The material passing 130 between the grinding-rollers C and D is ground by the latter, and then falls into the hollow base A, from which it can be transferred by any suitable means to a second mill of similar construction and shown in Fig. 9.

This operation is repeated and the stock sent forward from one set of rollers to another until any required degree of fineness is acquired. Dust arising during the process of 5 grinding settles in the ends of the grinding-rollers C and D and passes into the dust-spouts R and R', held in the ends of the said grinding-rollers C and D, and each provided with a scraper R² nearly in contact with the 10 inside of the respective grinding-roller C or D. (See Figs. 3 and 4.)

As shown in Fig. 9, any number of such grinding-mills may be arranged in a line or in 15 lines and coupled together, and may be alternately provided with rolls large and small in diameter. The peripheries of the grinding-rollers may be provided with separate cylindrical steel faces, either corrugated or smooth, or may be cast with their faces chilled. By 20 thus arranging a number of grinding-mills in a line or in lines and coupled together it is intended to produce a reduction-machine for reducing grain, to which power may be applied at one end, preferably by coupling directly 25 to the motor or power shaft. The parts of large diameter coupled to this shaft may be called the "primary" movers or drivers and reducers and may be so proportioned in size as to work in conjunction with the alternately 30 small parts in the same line and the alternate large and small parts in the secondary line and cause the secondary line to properly revolve without the aid of belts or gears and at the same time to maintain a proper or 35 any required differential between the grinding-faces. By this means the journal-bearings are relieved from the strain of drive belts or gears, and also from the strain of belts or gears used to produce the difference in speed. 40 By this arrangement it is evident that there is a great saving of power and that it is much easier to keep the journal-bearings from heating and causing the grinding-faces to get out of parallel, and also that the time usually lost 45 in mending belts, &c., when torn, or laces when broken, or the belts when they become too long or too loose, can be saved.

It is further evident that by the combination of the hollow grinding parts with the 50 openings in the ends of the casings and the spouts R and R' fixed therein and the scrapers attached that the hot air will be caused to pass out from the grinding parts and to relieve them and also the journals from the heat 55 caused by grinding, which would otherwise become excessive and overheat the stock and the journals. By this arrangement it is obvious that a still further increase of capacity may be acquired.

60 Having thus fully described my invention,

I claim as new and desire to secure by Letters Patent—

1. In a grinding-mill, the combination, with grinding-rollers provided with friction-pulleys on their ends, of screws H², pulleys H, 65 mounted in the screws and engaging the pulleys of one of the grinding-rollers, pivoted nuts H³, into which the screws H² work, and the rings I, engaging the pulleys on one of the grinding-rollers and the pulleys H, substantially 70 as herein shown and described.

2. In a grinding-mill, the combination, with a roller supporting hangers, of the collars P', engaging the lower ends of the hangers, screw-rods P², working in said collars, collars 75 P⁴, mounted on the eccentric ends Q' of the shaft Q and into which the rods P² screw, the jam-nuts P⁵ on the screw-rods, and the rod Q², secured to the shaft Q, substantially as 80 herein shown and described.

3. In a grinding-mill, the combination, with a roller supporting hangers, having their lower ends slotted, and screws engaging the slotted ends of the hangers for adjusting them vertically, of the collars P', engaging 85 the lower ends of the hangers, screw-rods P², working in said collars P', the shaft Q, having eccentric ends Q', the collars P⁴, mounted on the eccentric ends of the shaft and into which the rods P² screw, and the rod Q², secured to the shaft Q, substantially as and for 90 the purpose set forth.

4. In a grinding-mill, the combination, with a grinding-roller having an annular recess in its periphery, of a second grinding-roller 95 held in frictional contact with the stock passing between it and said first-named grinding-roller and provided on its periphery with an annular offset fitting into the annular recess of the said first-named grinding-roller, 100 and dust-spouts held in both open ends of the said grinding-rollers, substantially as shown and described.

5. In a grinding-mill, the combination, with a grinding-roller having an annular recess in 105 its periphery, of a second grinding-roller held in frictional contact with the stock passing between it and said first-named grinding-roller and provided on its periphery with an annular offset fitting into the annular recess of the said first-named grinding-roller, 110 dust-spouts held in both open ends of the said grinding-rollers, and scrapers formed on the said dust-spouts and nearly engaging the inside of the said rollers, substantially as 115 shown and described.

LEGRAND D. HARDING.
